UNITED STATES PATENT OFFICE.

WILLIAM MARCROFT, OF CRANSTON, RHODE ISLAND, ASSIGNOR, BY MESNE ASSIGNMENTS, TO UNIVERSAL WINDING COMPANY, OF BOSTON, MASSACHUSETTS, A CORPORATION OF MASSACHUSETTS.

WINDING-MACHINE.

1,236,464.

Specification of Letters Patent. Patented Aug. 14, 1917.

Application filed December 23, 1914. Serial No. 878,765.

To all whom it may concern:

Be it known that I, WILLIAM MARCROFT, a citizen of the United States, residing at Cranston, in the county of Providence and State of Rhode Island, have invented certain new and useful Improvements in Winding-Machines, of which the following is a specification.

My invention relates to winding machines and consists particularly of improvements in the mechanism for traversing the thread-guide which lays the yarn in place on the cop or quill. The object of my improvement is to provide automatic means for gradually lessening the extent of traverse of the thread-guide during the winding operation to cause the cop or quill to be wound with tapered or conical ends. A further object of my improvement is to provide a traverse-shortening mechanism which can be applied to standard types of machines now in general use without requiring any material alteration in the structure or arrangement of the basic machine.

The invention is fully described in the following specification, illustrated by the accompanying drawings, in which like reference characters designate like parts.

In the drawings:—

Figure 1 is a front elevation of a well-known type of winding machine showing my improved traverse-controlling mechanism applied thereto;

Fig. 2 is an enlarged, side view of the essential elements of my improved device;

Fig. 3 is an enlarged, plan view of the same;

Fig. 4 is an enlarged elevation of the thread-guide and its connected parts;

Fig. 5 is an enlarged, perspective view of a part of the guide-mounting through which the thread-guide is connected to the traverse-bar;

Fig. 6 is a similar view of another part of the guide-mounting; and

Fig. 7 illustrates the type of cop or quill wound on machines fitted with my improved mechanism.

Referring to Fig. 1, the basic or main machine, as here shown, is of a well known type substantially like that described and illustrated in United States Patent No. 589,587, granted to S. W. Wardwell, Sept. 7, 1897, and widely used for winding shuttle

cops or quills by the Universal or V-wind system. It consists essentially of a rectangular frame A having parallel uprights *a*, *a* formed with bearings for the horizontal winding-spindle B and cam-shaft C. The spindle B is driven through the medium of a driving-pulley *b* adapted to be rotated from a suitable belt, not here shown, which can be shifted onto the loose pulley *b'* when it is desired to arrest the operation of the machine. The spindle B also carries a pulley *b*² which is connected by a belt *b*³ to a pulley *b*⁴ on a shaft D. The shaft D is mounted to rotate in bearings on a frame *d* which is pivoted at *d'*, *d'* on the cam-shaft C. At the left-hand end the shaft D carries a pinion *d*² which meshes with a gear *c* on the cam-shaft C. The pulley *b*⁴ is preferably of the expansible type commonly used on winding machines of this kind and can be adjusted to vary the diameter of its rim by simply turning the hand-nut *b*⁵. Through this adjustment the ratio of speed between the spindle B and the cam-shaft C can be varied to regulate the laying of the yarn or thread by the reciprocating thread-guide in a manner well known to those versed in the art.

The cam C' is mounted fast on the shaft C and is driven thereby, through the connections above described, to impart reciprocation to a horizontal traverse-bar E. The bar E is arranged parallel with the winding-spindle B and is mounted to slide longitudinally in bearings *a'*, *a'* of the frame A. The bar E is preferably arranged to project from both sides of the frame A to adapt it to carry one or more thread-guides G at either end so that the machine can be arranged to wind a plurality of quills at one time, one or more being supported on each end of the winding-spindle B. As both ends of the machine are similar, however, I have preferred to here illustrate the traverse-mechanism for one quill only, it being understood that this mechanism may be duplicated on the opposite side of the frame A.

Arranged in the rear of the traverse-bar E and supported fixedly in bearings *a*² of the frame A, see Fig. 2, is a horizontal rod F extending parallel with the rod E. On the outer end of the rod F is supported a bracket H which carries an end-bearing *h* for the cop-tube *z*, see Fig. 2. The end-

bearing h preferably takes the form of a live spindle rotatable in a bushing h' and projecting therefrom to enter the bore of the tube z . The opposite end of the tube z is supported on the reduced end b^6 of the winding-spindle B and is preferably formed with a slot z' which is engaged by a key or spline b^7 on the spindle to rotate the tube. The bushing h' is retractable in the bracket H to allow the insertion and removal of the tube z as usually provided for in machines of this type.

The thread-guide G is mounted on the traverse-bar E through the means of an arm or holder G' arranged to swing about the axis of the bar to allow the guide to move outward away from the surface of the cop-tube as the yarn is built up thereon. Referring to Fig. 1, the traverse-bar E is reciprocated from the cam C' through the engagement of the groove c' in the latter with a roll i carried by a cross-head I attached to the bar.

Heretofore it has been the common practice to reciprocate the thread-guide with a constant length of traverse throughout the winding of the cop or quill. This results in building up the ends of the quill with a flat formation; that is, the ends will be square with the axis of the quill. In winding certain varieties of thread, such as hard, glossy silk and other like materials, it has been found very difficult to build the quills with perfect ends while employing this style of winding. Owing to the slippery quality of the thread the coils of winding are liable to slide off the ends of the quill and fall down on to the tube, thereby causing a malformed package from which the yarn cannot be unwound without snarling and breaking. To obviate this defect in the quills it has before been proposed to wind them with tapered or conical ends as illustrated particularly in Fig. 7, but in most cases it has required special machines built particularly for winding in the manner described to produce taper-ended quills of the form shown. My new improvement makes it possible to adapt a usual type of quill-winder for this style of winding and the manner of carrying out the improvement will next be described:

It will be observed from the foregoing explanation that the traverse-bar E is reciprocated from the cam C' with a constant extent of traverse throughout the whole operation of the machine. As usually provided in machines of this type the thread-guide G has a fixed relation to the traverse-bar, that is, longitudinally thereof, and hence the guide will be given a constant extent of traverse throughout the complete winding operation for each cop. In my present improvement I maintain the reciprocation of the traverse-bar constant, so as

not to require any alteration in the main traversing-mechanism, but by providing means for periodically oscillating the guide in a plane parallel with the bar E effect the desired gradual shortening of traverse of the guide from start to finish of the winding. To adapt the guide G for this oscillatory movement with respect to the traverse-bar E I pivot it on an axis crossing the line of movement of the bar as shown more particularly in Figs. 2 and 4. The guide G , as before described, comprises an arm or guide-holder G' which, as shown in Fig. 4, embraces the "button" or element g provided with a notch g' through which the yarn passes. Secured to the guide-arm G' in line with the notch g' is a guide-eye g^2 illustrated in Fig. 2, but omitted in the other views for the sake of clearness. The mid-portion of the guide-holder or arm G' is formed in somewhat of a "banjo" shape continued in the downwardly extending arm g^3 provided with a suitable hole through which the pivot-stud g^4 passes. The stud g^4 is screwed into the depending arm or lug g^5 of a supporting-member or sleeve g^6 , shown in detail in Fig. 6, which is adapted to surround the traverse-bar E and free to turn thereon. Preferably, the stud g^4 is shouldered to adapt it to be set up against the face of the lug g^5 so that the arm G' will be allowed free play to oscillate about the axis of the stud. The sleeve g^6 while free to turn on the traverse-bar E is held longitudinally thereof by means of a second bifurcated sleeve or bearing J shown in detail in Fig. 5. The sleeve J is preferably constructed of sheet-metal bent to form two spaced-apart, ring-like bearings j, j connected by a cross-piece or brace j' . The bearings j, j do not completely encircle the bar E , but are formed with laterally-projecting, bent-over ears j^2 adapted to be clamped to the cross-piece j' by means of the screws j^3 . Through this means the bearings j, j are caused to bind on the rod E to secure the member J in position. As before stated the guide-arm sleeve g^6 is located on the bar or rod E between the bearings j, j . A flat, steel spring K is secured to the cross-piece j' of the member J by means of the screws j^3 , see Fig. 3, and is formed with a tail-piece k which reaches down to bear on the surface of the sleeve g^6 . Through this arrangement a slight friction is applied on the sleeve g^6 to resist its turning movement on the bar E , thereby tending to hold the guide-arm G' in whatever position it may be adjusted. Projecting upwardly from the cross-piece j' of the member J is an arm or finger j^4 on which is pivoted an L-shaped member L . Preferably, the member L is pivoted on a headed stud l riveted through the arm j^4 . Riveted through the upright arm of the member

L is a bar or rod M which for the sake of convenience I term the radius-rod. The rod M passes through an elongated slot *n* in a swiveled bearing-member N mounted 5 on the guide-arm G', see Fig. 4. Preferably the member N is cylindrical in shape and is formed with end pintles *n'*, *n'* seated in bearings in the lugs *g'*, *g'* which project from the rear face of the arm G', see Fig. 2.

10 The radius-rod M projects through the central opening in the arm G' and its opposite end is slidably mounted in a swiveled bearing-member O. The bearing-member O is pivotally mounted at the end of an 15 adjustable rod P held in a clamp-member R. The end of the rod P is flattened off at *p* and provided with a lateral hole in which the reduced shank *o* of the member O is free to turn. The projecting end of the shank *o* 20 is reduced in diameter at *o'* and riveted through a washer *o''* which serves to hold the member O in place while allowing it to turn on the rod P. The clamp-member R is formed to straddle a rod S which extends 25 in a horizontal direction in front of and parallel with the winding-spindle B, see Figs. 1 and 2. The rod S is supported in bearings at the ends of two arms *t*, *t* which form part of a bracket or frame T secured 30 to the top of the main frame A of the machine by means of the screws *t'*, *t'*. Suitable set-screws *s*, *s* are screwed into the bearings on the arms *t*, *t* and tightened against the rod S to hold it in position. In Fig. 1 35 the projecting ends of the rod S are shown as partly broken away to prevent obscuring the other parts of the machine. As shown more particularly in Figs. 2 and 3, the clamp-member R is formed with two arms 40 or lugs *r*, *r* provided with openings through which the rod P extends in position to lie across the top of the rod S. Preferably, the rod P is flattened off on its under side at *p'*, as shown in Fig. 1, and the rod S is also 45 flattened off at *s'* to form more extended bearing surfaces where the rods cross each other. The flat portion *s'* on the rod S is arranged at an angle to the horizontal so that the rod P and radius-rod M incline downwardly to 50 a point just above the traverse-bar E, see Fig. 2. A set-screw *r'* is screwed through the clamp-member R with its end bearing against the rod S and through this means the rod P can be clamped against the flattened 55 surface of the rod S to hold it firmly in place. By loosening the set-screw *r'* the clamp R can be adjusted longitudinally of the rod S and the rod P can be adjusted longitudinally of its bearings *r*, *r* so as to 60 regulate the position of the member O which serves as a pivot for the radius-rod M.

It will be understood from the foregoing explanation that when a usual type of winding machine such as herein first described is 65 to be fitted for winding taper-ended quills

of the form shown in Fig. 7, certain parts are added to the basic or main machine. That is to say, the regular type of thread-guide ordinarily used on the machine is replaced by the one here shown which is attached to the standard traverse-bar E as described. The bracket T is fastened to the frame A by the screws *t'* which fit tapped holes already provided in the standard machine. The rod S is next adjusted in the 70 bracket R and the mechanism carried thereby is set in place and connected with the guide G. After the parts have been properly correlated and adjusted the machine is ready for use and operates as follows:

The cop-tube *z* is placed in position by seating one of its ends on the end of the winding-spindle B and its opposite end on the spindle bearing *h*. It is here called to attention that instead of winding the cops 85 or quills on the wooden tubes *z*, as shown, they might be wound on paper shells or tubes as sometimes provided. For instance, where more than one quill is to be wound on each end of the winding-spindle the main 90 spindle B is extended to the proper length to accommodate as many paper cop-tubes as desired. For the sake of clearness the operation of one thread-guide only will be here described and that in connection with the 95 arrangement illustrated in the drawings. As here arranged the guide G is first adjusted with the rounded face of its "button" *g* bearing against the surface of the cop-tube *z* and the thread or yarn is led down from 100 its source of supply, generally arranged above, but not here shown, and threaded through the eye *g''* and notch *g'*, see Fig. 1. The free end of the yarn *y* is then attached to the tube *z*, and the machine is ready to 105 be started. This is accomplished by shifting the driving-belt onto the "fast" pulley *b*, when the spindle B will rotate the tube *z* and, through its connections with the cam-shaft C, will drive the cam C' to reciprocate 110 the traverse-bar E. As the bar E slides back and forth in its bearings *a'*, *a'* the guide G', held longitudinally thereon by the member J, is carried with it and the thread passing through the guide-notch will be laid on the 115 tube *z* in open helices to build up cross-wound layers in the manner well known to those versed in the art. As the guide G traverses back and forth parallel with the axis of the winding-spindle the member J, mounted on the bar E, will carry the end of the radius-rod M to which it is attached back and forth with an oscillating movement as 120 illustrated by the dash-lines in Fig. 3. During this swinging movement of the rod M its supporting member L turns on the pivot *l* while at its opposite end the swiveled member O allows both a pivotal and sliding movement of the rod. The member N also 125 swings on its pivot as the guide moves back 130

and forth to accommodate itself to the oscillation of the rod M. Now, as the yarn builds up on the tube z it forces the guide G away from the axis of the winding-spindle 5 in a well-known manner, this movement being provided for by the turning of the guide-supporting member g^o on the rod E. At the beginning of the winding, when the thread-guide G is bearing against the tube z, the 10 guide-arm G' will stand substantially at right-angles to the radius-rod M, that is, viewing the parts as shown in Fig. 2. Under these conditions the arm G' will also remain in substantially perpendicular relation 15 to the traverse-bar E, viewing the parts as shown in Fig. 4, throughout the whole extent of its traverse. In other words, at the commencement of the winding the thread-guide arm G' will remain in fixed relation to 20 the bar E and hence the guide-button g will have an extent of traverse equal to the whole length of traverse of the bar. When, however, the guide-arm G' begins to swing outwardly away from the axis of the tube z, 25 due to the growth of the winding, its controlling-member N will slide along the radius-rod M toward the axis of oscillation of the latter, and this will have the effect of changing the longitudinal position of the 30 thread-guide with respect to the bar E. That is to say, as the controlling-member N slides toward the pivot-point of the radius-rod M, it will cause the guide-arm G' to be displaced longitudinally of the axis of the 35 bar E at the extremes of travel of the latter. In other words, the guide-arm G' will be caused to rock inwardly at the extremes of 40 traverse of the bar E, as shown in Fig. 1, so that the effective length of traverse of the guide G at its point of delivery, i. e., the notch g' of the button g, will be gradually 45 shortened. Stated briefly, the guide-arm G', influenced by the growth of the winding, slides back on the radius-rod M and the angular position of the rod at each end of 50 the traverse of the bar E acts to tilt the guide-arm away from the ends of the cop so that the yarn will be wound with progressively shortened layers to build up a cop or quill with tapered ends.

By adjusting the rod P longitudinally in its bearings the relation of the pivot of the radius-rod M to the guide-arm G' can be varied so that angular movement of the rod 55 is altered to give a greater or less extent of oscillation to the guide G on the bar E; and in this way the degree of alteration in the length of layers of the winding can be regulated as required. By regulating the 60 change in the length of traverse of the guide in this manner the amount of taper at the ends of the cop can be controlled according to the form required for different classes of material. Through this adjustment it is 65 also possible to adapt the machine for dif-

ferent lengths of cops in accordance with the particular length of throw of the cam C' being used on the machine.

I am aware that it is not new in the art to wind quills or cops with conical or 70 tapered ends. I am also aware that it has before been proposed to pivotally mount the thread-guide on the traverse-bar to provide for an oscillating movement thereof in addition to its main, straight-line traverse-motion with the bar. The object of my 75 present improvement is to provide a device of this sort which can be readily applied to machines now generally in use without requiring machine work or special fitting of 80 the main elements of the winding mechanism. In my previous application for U. S. Patent, Serial 780,275, filed July 21, 1913, I have disclosed an invention having the same object in view, but in the present improvement I accomplish the purpose with 85 a more simple and compact mechanism, capable of a wider range of adjustment, and adapted to be manufactured at a much less cost.

Various modifications might be made in the form and construction of the parts of my new device without departing from the spirit or scope of the invention; therefore, without limiting myself to the exact embodiment shown and described, what I 95 claim is:—

1. In a winding machine, the combination with a rotating winding-spindle and a longitudinally reciprocating traverse-bar, of 100 a thread-guide mounted on said bar to adapt it to be reciprocated therewith and to recede from the axis of the winding-spindle as the cop increases in diameter, and means operated through the receding movement of the guide to cause the latter to be periodically displaced longitudinally of the 105 traverse-bar to effect a progressive shortening of the layers of winding in the cop.

2. In a winding machine, the combination with a rotating winding-spindle and a longitudinally reciprocating traverse-bar, of a thread-guide mounted on said bar to 110 adapt it to be reciprocated therewith and to recede from the axis of the winding-spindle as the cop increases in diameter, and means operated by the receding movement of the 115 guide to cause it to be displaced longitudinally of the bar during each traverse of the latter to effect a gradual shortening of the 120 layers of winding in the cop.

3. In a winding machine, the combination with a rotating winding-spindle and a longitudinally reciprocating traverse-bar, of a thread-guide mounted on said bar to 125 adapt it to be displaced longitudinally thereof and arranged to recede from the axis of the winding-spindle as the cop increases in diameter, and means controlled by the receding movement of the guide to 130

cause an increasing differential movement of the traverse-bar and guide at the extremes of traverse of the latter to effect a progressive shortening of the layers of winding in the cop.

4. In a winding machine, the combination with a rotating winding-spindle, of a thread-guide adapted to recede from the axis of the winding-spindle as the cop increases in diameter, and to rock in a plane parallel with its path of movement, means to reciprocate the guide bodily with a straight-line movement parallel with the surface of the cop, and means to rock the guide inwardly from its extremes of traverse during its movement of reciprocation, said means controlled by the receding motion of the guide to cause it to wind with a progressively decreasing extent of traverse from start to finish of the cop.

5. In a winding machine, the combination with a rotating winding-spindle and a reciprocating thread-guide adapted to recede from the axis of the winding-spindle as the cop increases in diameter, of means to reciprocate the guide bodily in a rectilinear path parallel with the surface of the winding, and means to shift the guide inwardly from its extremes of traverse with a differential movement with respect to its reciprocating-means, said means operated by and through the receding movement of the guide to effect a gradual shortening of the layers of winding in the cop.

6. In a winding machine, the combination with a rotating winding-spindle and a reciprocating traverse-bar, of a thread-guide mounted on said bar to adapt it to recede from the axis of the winding-spindle as the cop increases in diameter and to be displaced longitudinally of the bar during its reciprocation therewith, and means operated through the receding movement of the guide to cause it to be shifted inwardly from its extremes of traverse with a gradually increasing extent of displacement to effect a progressive shortening of the layers of winding from start to finish of the cop.

7. In a winding machine, the combination with a rotating winding-spindle and a reciprocating traverse-bar, of a thread-guide mounted on said bar to adapt it to recede from the axis of the winding-spindle as the cop increases in diameter and also pivoted on the bar to adapt it to be rocked in a plane parallel therewith, and means engaging the guide to cause it to be rocked inwardly at its extremes of traverse on the bar with a gradually increasing extent of movement as it recedes from the axis of the winding-spindle to cause it to lay the yarn on the cop with a progressively shortened traverse.

8. In a winding machine, the combination with a rotating winding-spindle and a reciprocating traverse-bar, of a thread-guide piv-

oted on said bar to rock in a plane parallel with its line of movement and arranged to recede from the axis of the winding-spindle as the cop increases in diameter, and means engaging the guide and controlled through its receding movement to cause the guide to be rocked inwardly with a gradually increasing extent of movement at its extremes of traverse to effect a progressive shortening of the layers of winding from start to finish of the cop.

9. In a winding machine, the combination with a rotating winding-spindle and a reciprocating traverse-bar, of a thread-guide mounted on said bar to adapt it to recede from the axis of the winding-spindle as the cop increases in diameter, means for pivoting said guide on the bar to adapt it to be displaced thereon in a plane parallel with its line of movement, a radius-rod connected with the bar to be oscillated thereby about a fixed pivot, and connections between the radius-rod and the guide to cause the latter to be moved inwardly at its extremes of traverse with a gradually increasing extent of movement as it recedes from the winding-spindle to effect a progressive shortening of the layers of winding in the cop.

10. In a winding machine, the combination with a rotating winding-spindle and a reciprocating traverse-bar, of a thread-guide pivoted on the bar to swing in a plane parallel therewith and arranged to recede from the axis of the spindle as the cop increases in diameter, a radius-rod connected with the traverse-bar to be oscillated thereby, and means on the thread-guide engaging the radius-rod to cause the latter to swing the guide inwardly at its extremes of traverse to effect a gradual shortening of the layers of winding from start to finish of the cop.

11. In a winding machine, the combination with a rotating winding-spindle, of a thread-guide adapted to recede from the axis of the spindle as the cop increases in diameter, means to reciprocate the guide bodily in a rectilinear path parallel with the surface of the winding, a radius-rod adapted to be oscillated from the reciprocating-means about a fixed axis, and means on the guide engaging the radius-rod to cause an increasing differential movement between the reciprocating-means and the guide whereby the traverse of the guide is progressively shortened from start to finish of the cop.

12. In a winding machine, the combination with a rotating winding-spindle, of a thread-guide adapted to recede from the axis of the spindle as the cop increases in diameter, means for reciprocating the guide bodily in a rectilinear path parallel with the surface of the winding, and means to shift the guide inwardly from its extremes of traverse to shorten its effective length of

reciprocation, said means comprising a radius-rod oscillated from the reciprocating-means and arranged with the guide adapted to move on the rod toward the axis of oscillation of the latter during the growth in the winding.

13. In a winding machine, the combination with a rotating winding-spindle, of a traverse-bar adapted to be reciprocated longitudinally of the spindle, a thread-guide pivoted on the traverse-bar to adapt it to be rocked in a plane parallel with the axis of the winding-spindle and also arranged to swing on the bar to allow it to recede from the axis of the winding-spindle, a radius-rod pivotally connected to the traverse-bar at one end and having its opposite end slidably mounted in a pivot-bearing, and means pivoted on the thread-guide and adapted to slide on the radius-rod toward the outer pivot of the latter as the guide is moved by the growth in diameter of the winding.

14. In a winding machine, the combination with a rotating winding-spindle, of a reciprocating traverse-bar, a guide-member pivoted to turn on the bar but held longitudinally thereof, a thread-guide pivoted on the guide-member to adapt it to swing in a plane parallel with the traverse-bar, a radius-rod hingedly connected to the traverse-bar at one end, a pivoted bearing-member for supporting the opposite end of the radius-rod, and a swiveled bearing-member mounted on the thread-guide to adapt it to slide on the radius-rod to move toward the pivot of the latter as the guide recedes from the axis of the winding-spindle.

15. In a winding machine, the combination with a rotating winding-spindle, of a reciprocating traverse-bar, a thread-guide mounted on the bar to adapt it to recede from the axis of the winding-spindle as the cop increases in diameter and also pivoted on the bar to rock in a plane parallel therewith, a radius-rod pivotally connected at one end to the traverse-bar, a pivoted bearing for the opposite end of the radius-rod, means for mounting said bearing to adapt it to be adjusted in relation to the traverse-bar, and means on the thread-guide engaging the radius-rod to control the rocking movement of the guide during its reciprocation with the traverse-bar.

16. In a winding machine, the combination with a rotating winding-spindle, of a thread-guide adapted to recede from the

axis of the winding-spindle as the cop increases in diameter, means to reciprocate the thread-guide with respect to the winding-spindle, means to periodically shift the thread-guide inwardly from its extremes of traverse during its reciprocation comprising a radius-rod engaging the guide and oscillated from the reciprocating-means, a pivot-bearing about which the radius-rod oscillates, and means to adjust said bearing in position to regulate the angular movement of the radius-rod.

17. In a winding machine, the combination with a rotating winding-spindle, of a reciprocating traverse-bar, a guide-member mounted to turn on the bar, means to hold said guide-member from longitudinal movement on the bar, a thread-guide pivoted on the guide-member to adapt it to rock in a plane parallel with the traverse-bar, a radius-rod, a swiveled bearing connecting one end of the radius-rod to the traverse-bar, a bearing pivotally mounted on the thread-guide to adapt it to slide on the radius-rod, a pivoted bearing for the outer end of the radius-rod, and means for mounting said last named bearing to adapt it to be adjusted both laterally and longitudinally of the traverse-bar.

18. In a winding machine, the combination with a main frame, of a winding-spindle adapted to rotate in bearings on the frame, a traverse-bar adapted to be reciprocated in bearings on the frame, a thread-guide mounted on the traverse-bar to swing in a plane at right-angles thereto and also adapted to be rocked on the bar in a plane parallel therewith, a bracket secured to the frame, a rod supported on the bracket parallel with the traverse-bar, a bearing supported on the rod and adjustable longitudinally thereof, a second rod supported by the bearing to adapt it for longitudinal adjustment at right-angles to the first rod, a bearing-member pivoted at the end of said second rod, a radius-rod slidably in said pivoted bearing, means to pivotally connect the opposite end of the radius-rod with the traverse-bar, and a pivoted bearing on the thread-guide engaging the radius-rod to adapt it to slide thereon.

In testimony whereof I affix my signature in presence of two witnesses.

WILLIAM MARCROFT.
